(57) **CLAIM**

The ornamental design for a visual ear wax removal tool, as shown and described.

DESCRIPTION

FIG. 1 is a perspective view of a visual ear wax removal tool, showing my new design;

FIG. 2 is another perspective view thereof;

FIG. 3 is an enlarged view of portion 3 shown in FIG. 1;

FIG. 4 is a front view thereof;

FIG. 5 is a rear view thereof;

FIG. 6 is a left side view thereof;

FIG. 7 is a right side view thereof;

FIG. 8 is an enlarged top plan view thereof; and,

FIG. 9 is an enlarged bottom plan view thereof.

The broken line showing of the visual ear wax removal tool is for the purpose of illustrating article and forms no part of the claimed design.
